UNITED STATES PATENT OFFICE.

ARTHUR E. BREITENFELT, OF HARTFORD, WISCONSIN.

ADJUSTABLE TAPPET-ROD HEAD.

Application filed May 8, 1925. Serial No. 28,857.

This invention relates to adjustable tappet rod heads.

The tappet rods used in internal combustion engines give trouble due to relative variations in the length of the rods, and the cooperating parts of the engine, such variation being due to several causes such, for instance, as temperature changes of the parts and wear. The result of this variation is a noisy operation of the tappet rod which is annoying and which also slightly varies the action of the engine and alters its efficiency.

This invention is designed to overcome the above noted defects, and objects of the invention are to provide a tappet rod head which will cause a quiet action of the tappet rod under all conditions, which is provided with a yielding portion and with an adjustable member to vary the degree of yielding of such portion, and which is provided with a very simple and reliable locking device for holding the adjustable member in correct position against inadvertent motion.

An embodiment of the invention is shown in the accompanying drawings, in which:

Figure 1 is an elevation partly broken away of the tappet rod head showing it in relation to the valve and tappet rod.

Figure 2 is an enlarged section through the lower end of the head.

Figure 3 is a bottom view of the tappet rod head.

Figure 4 is a sectional view on the line 4-4 of Figure 2.

The tappet rod head has been shown as forming a portion of the valve structure, but it is to be understood that it may be located upon and carried by the tappet rod itself, if desired,—one form of the invention being considered sufficient for the purpose of illustration.

Referring to the drawings, particularly Figure 1, it will be seen that the usual tappet rod 1 is employed to operate the valve 2. However, a head is interposed between the valve and the rod. This head comprises a cylindrical portion 3 which in the form shown is a unitary structure with the valve. This cylindrical member 3 has a closed upper end and an open internally threaded lower end for the reception of the threaded plug 4. This plug is provided with a wrench receiving lower portion, as shown, and is provided with an aperture 5 opening through its lower end, and with a larger

aperture 6 opening through its upper end. This larger aperture is internally threaded adjacent its upper end, and receives the externally threaded cap 7 which is preferably of shell like formation and provided with an aperture 8, as shown in Figure 2.

The upper end 9 of the cap 7 is squared or otherwise shaped to receive a wrench to permit relative adjustment between the cap 7 and the plug 4. It is to be noted that means are provided for locking these parts temporarily against motion, such means comprising slots 10 formed in the upper end of the plug 4, and a slot 11 formed at right angles to the slots 10 and in the portion 9.

A clip or locking member 12 is provided with arms at right angles to each other, and these arms are adapted to be slipped into the slots 11 and 10 in the members 9 and 4, respectively, and to thus temporarily lock the plug 4 and cap 7 against relative motion. The locking member 12 cannot be displaced when the plug is screwed into the cylindrical portion 3 of the head, as shown in Figure 4, as the inner cylindrical walls of the member 3 limit lateral motion of the member 12. The plug is held against motion with relation to the cylindrical portion 3 by means of a lock nut 13, as shown particularly in Figures 1 and 2.

It is preferable to provide the lower end of the head 3 with flattened portions or cut-away portions 14 for the reception of a wrench to aid in the convenient manipulation of the parts.

A plunger 15 is provided which has one portion projecting through the aperture 5 in the plug 4, and which has a reduced portion 15' located within the aperture 5 in the plug and preferably guided within the aperture 8 of the cap 7, as shown in Figure 2.

This plunger is provided with an integral collar 16 intermediate its ends which is adapted to rest upon the shoulder formed at the point of union of the aperture 6 and the aperture 5 through the plug 4.

A helical spring 17 surrounds the reduced portion 15' of the plunger and bears at opposite ends against the collar 16 and the lower end of the cap 7. It is clear that the exact adjustment of the spring pressure may be easily secured by screwing the cap 7 inwardly or outwardly of the plug 4 when the plug is removed from the cylindrical

member 3. Thereafter, the locking member 12 is slipped into place and the plug reinserted in the cylindrical member.

In operation the tappet rod 1 bears against the lower end of the plunger in the form shown and lifts the valve through the medium of the spring 17.

It is to be noted that the spring 17 accommodates slight variations due to wear and other variations, which alter the length of the rod and thus insures a very quiet operation of the tappet rod at all times.

From the foregoing description and accompanying illustrations, particular attention is called to the fact that this invention in brief terms is primarily directed to a yielding plunger associated with a practical adjustable feature, it being understood that the units comprising the plunger and its associated adjustable element can be readily applied to either an overhead motor valve structure or that of the ordinary type.

Although the invention has been described in considerable detail, it is to be understood that the invention may be variously embodied and is, therefore, to be limited only as claimed.

I claim:

1. A tappet rod head comprising a cylindrical member having a closed end and an open end, a plug screwed into the open end, a plunger slideable through said plug, a helical spring surrounding said plunger and urging it outwardly, and means for adjusting the pressure of said spring.

2. A tappet rod head comprising a cylindrical member having a closed end and an open end, a plug screwed into the open end, a plunger slideable through said plug, a helical spring surrounding said plunger

and urging it outwardly, means for adjusting the pressure of said spring, and a locking member for holding said adjusting means against motion.

3. A device adapted for use with tappet rods comprising an elongated cylindrical member having an open end, a plug screwed into said open end and having an enlarged aperture through its inner end, and a smaller aperture through its outer end, a plunger fitted within said plug and projecting through the smaller aperture and having a collar formed thereon, a spring positioned within the larger aperture of said plug and bearing against said collar, and a cap screwed into said plug and adjustably compressing said spring.

4. A device adapted for use with tappet rods comprising an elongated cylindrical member having an open end, a plug screwed into said open end and having an enlarged aperture through its inner end, and a smaller aperture through its outer end, a plunger fitted within said plug and projecting through the smaller aperture and having a collar formed thereon, a spring positioned within the large aperture of said plug and bearing against said collar, a cap screwed into said plug and adjustably compressing said spring, said plug and said cap having right angle slots formed therein, and a right angle member having its arms removably seated in said slots to hold said cap and plug against relative motion.

In testimony that I claim the foregoing 75 I have hereunto set my hand at Hartford, in the county of Washington and State of Wisconsin.

ARTHUR E. BREITENFELT.
